(57) **CLAIM**

The ornamental design for an electric induction power supply, substantially as shown and described.

DESCRIPTION

FIG. 1 is a front perspective view of the electric induction power supply;

FIG. 2 is a back perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left elevation view thereof; and,

FIG. 8 is a right elevation view thereof.
